UNITED STATES PATENT OFFICE.

WALTER C. HADLEY, OF NEW YORK, N. Y., ASSIGNOR TO AMERICAN PRINTING COMPANY, OF FALL RIVER, MASSACHUSETTS, A CORPORATION OF MASSACHUSETTS.

DESIGN DEVELOPMENT.

Application filed April 30, 1923. Serial No. 635,680.

To all whom it may concern:

Be it known that I, WALTER C. HADLEY, a citizen of the United States, and a resident of the city of New York, borough of Manhattan, in the county of New York and State of New York, have invented new and useful Improvements in Design Development, of which the following is a full, clear, and exact description.

10 The present invention relates broadly to that class of optical instruments known as kaleidoscopes, and more particularly aims to provide an improved method and apparatus useful in design-generation as well as in 15 design-development and of particular value in textile designing.

In my co-pending application Sr. No. 635,689, filed April 30, 1923, I disclose and claim a method of and apparatus for the 20 kaleidoscopic generation of designs by the use of a projection beam, and further disclose in connection therewith a method and apparatus whereby a translucent sheet-like design-generating instrumentality or mother 25 sheet, even of limp and inelastic flexible material, as thin cloth, may be employed to generate a satisfactory design, may be treated so as to indicate subsequently the area of the sheet which created such design, 30 and so may be later turned over to a copying artist for reproduction into the finished design by the brush of such artist.

Once a design is generated from a mother sheet as aforesaid, and such design is 35 produced by the copying artist so far as configurations are concerned, it usually next becomes important to determine various color schemes to be adopted in applying the design to a textile fabric.

40 It is the prime object of the present invention to provide a novel and valuable method of developing a given design configuration, say one generated by the projection method and apparatus of my said co-pending application. Otherwise stated, an important 45 object of the invention is to provide a method of visually developing a previously created design, particularly in regard to various color schemes, so that various replicas 50 of the design, but each of a different color scheme, may be readily observed and com-

pared, and repeatedly so observed and compared.

A further object is to provide such a method, and one which, while fully adequate 55 to satisfy the important object above mentioned, involves the preparation, at a minimum of trouble and expense, of a design-developer means for a particular color scheme for an accepted design or for all the 60 different color schemes tentatively selected for the accepted design.

Still another object of the invention is to provide a small, compact, light and hence 65 easily portable apparatus designed for co-action with a design-developer means as above indicated; as for use by a salesman for the textile mill when interviewing customers. In this connection it may be explained that many mills do not manufacture 70 figured textiles until after the customer has given his order based on artists' sketches of different suggested designs and of the same designs according to various color schemes.

An incidental object of the invention is 75 to provide an apparatus of the above type, and one wherein simple and convenient means are incorporated for permitting the apparatus to be also used for design generation, in substitution for the method and apparatus of my said co-pending application 80 Sr. No. 635,689.

Thus it will be seen that the present invention, in aiming to satisfy the object last mentioned, has the further object of providing 85 a kaleidoscopic apparatus in which there may be used interchangeably, optical interponents of quite dissimilar types, that is, an optical interponent which is a design-generating instrumentality or mother sheet of the 90 kind described in my said co-pending application, and hereinafter called the mother sheet interponent, and a design-developing instrumentality or color-variation sheet, hereinafter called the color sheet inter- 95 ponent.

Various other objects will be in part obvious and in part specifically referred to hereinafter.

The invention will be more clearly understood from the following description, when taken in connection with the accom-

panying drawings, showing a preferred apparatus.

In said drawing,

5 Fig. 1 is a top plan view of the embodiment;

Fig. 2 is a vertical section, taken on line 2—2 of Fig. 1;

Fig. 3 is also a vertical section but taken on line 3—3 of Fig. 1;

10 Fig. 4 is a perspective view of a form of kaleidoscope unit or tube preferred to be used; and

15 Fig. 5 shows a kaleidoscopically created design such as would be seen were the eye applied to the upper end of the tube of Fig. 4 with the corresponding design-repeat element of Fig. 1 arranged relative to the lower end of said tube and then subjected to enough illumination to constitute said 20 element an optical interponent as aforesaid.

The method of design-development, and, at will, design-generation, according to the present invention, will be best understood 25 if first the apparatus shown in the drawings is described in detail.

On a main supporting structure 6, which is desirably a horizontal or shelf structure on legs 7, is positioned a tube 8. Such tube 30 may of course be designed to have any number of mirror or prism walls, to provide, as is well understood in the art, a reflecting chamber having a cross-sectional shape according to any regular or irregular polygon. In the present case, the tube 8 has 35 three mirrors 9, 10 and 10, and these mirrors are so relatively inclined as to present a reflecting chamber 11 having the cross-section of an equilateral triangle. Tube 8 is a bodily removable one to be supported 40 merely by gravity when placed in the apparatus as shown. The outer sleeve 12 of the tube has a flat square bottom-plate 13, provided with a triangular opening aligning with the bottom of the reflecting chamber. This opening is enlarged as indicated 45 at 14 in Figs. 1, 3 and 4. The mirror 9 is of the same length as the mirrors 10 but is set higher in the tube to provide at its 50 top a projecting wall to constitute a light shield or hood and to provide an opening for the bottom of the tube opposite a window 15 in the lower end of sleeve 12.

When tube 8 is in position in the apparatus as illustrated, the bottom plate 13 rests 55 on a bridge or platform 16, having an opening 17 surrounding the bottom of the reflecting chamber in the tube.

In the present case, the shelf structure 60 16 includes a frame-like shelf proper of wood having an opening 18; and platform 16 is conveniently a thin metal strip spanning the middle of this opening transversely of the apparatus.

65 Below said platform 16 is a second plat-

form 19, conveniently of wood, and hinged to the shelf structure as indicated at 20. Platform 19 is provided with an opening 21 shaped to align with the opening 17 through platform 16 when the platform 19 is swung up from the dot-and-dash location of Fig. 3 to the full-line one shown. When platform 19 is thus swung up, and a pivoted catch 22 is adjusted as shown in Fig. 3, the platform is held parallel with platform 16 but spaced below the same sufficiently to constitute a supporting means for any desired type of optical interponent to permit the latter to be shifted in a single plane relative to the reflecting chamber of the tube.

In combination with the supporting and guiding means thus provided by platform 19 for an optical interponent, there is provided a further guiding means for a certain type of interponent. This latter guiding means constitutes a means for limiting such interponent to movement in a predetermined path in said plane; and here includes a pair of continuous guiding devices or rails 23 and 24. These rails may be continued, beyond opening 18, as best indicated at 23' and 24' in Fig. 1.

On opposite sides of the main supporting or shelf structure 6, and in each case to one 95 side of the openings in platforms 16 and 19, are provided sources of illumination, as incandescent electric bulbs, 25 and 26.

The optical interponent illustrated, at 27, is a rather stiff paper or cardboard sheet 100 having drawn on areas 27' on the upper face of the sheet (or on separate sheets pasted or otherwise mounted on sheet 27), a plurality of design-repeat elements 28, identical as to configuration, but differing as to color scheme as indicated. Properly 105 to co-act with the rail structure here incorporated as the limiting means aforesaid, this sheet 27 is a strip-like member with the elements 28 arranged in column; and so that when the tube is properly set on platform 16, a straight-line shifting of sheet 27 a predetermined distance will accurately substitute one element 28 for another relative to the reflecting chamber of the tube, these elements are disposed on the sheet so that a particular characteristic 110 bounding line of one element is parallel to the corresponding bounding line of the adjoining element.

Cross straps 29 and 30, overlying rail portions 23 and 24 and 23' and 24', may be added to assist platforms 16 and 19 in holding interponent 27 to uniplanar extension at all times.

The method of the present invention, 125 preferably such a method that the real and only object thereof is a color comparison relative to a plurality of designs of the same configuration, is, when carried out 130

with the aid of the apparatus just described, substantially as follows:

A suitable configuration for a design-repeat element is assumed to have been already evolved, as by use of the apparatus of my said co-pending application Sr. No. 635,689, or otherwise. An optical interponent 27 is then prepared by an artist, so that a plurality of hand-drawn colored 5 design-repeat elements 28 are carried by the interponent as above described. Next a kaleidoscope tube is provided and arranged so as to permit application of the eye to an end of the tube to observe the interior 10 of the reflecting chamber and to admit light rays to the interior of the chamber. Finally, the tube and the interponent are relatively disposed so that the light rays aforesaid strike a selected one of the repeat 15 elements 28 and reflect an image of the colored design of such element onto each of the walls of the reflecting chamber of the tube, thereby to kaleidoscopically reproduce a complete design, such as that indicated in Fig. 5, and according to the color 20 scheme of the particular element 28 set to co-act with the tube. Interponent 27 may be shifted as required to substitute one repeat element 28 for another practically instantaneously, for comparing a large number 25 of different color schemes for a design previously approved as to configuration.

As hereinabove indicated, however, the invention provides a method of complete 30 design-creation, that is, a method involving not only design-development as to color scheme but a preliminary or initial design-generation as to configuration, and such a complete method of design-creation which 35 may be very conveniently and economically carried out with the assistance of the apparatus shown in the drawing. Such method of design-creation is substantially as follows: A mother sheet optical interponent (not shown, but having markings as 40 and for the purpose defined in my said co-pending application) is placed loosely between platforms 16 and 19; this interponent always being of the proper size to permit 45 the same to be shifted in its own plane by finger manipulation within opening 18. If the mother sheet is of cloth or similar flimsy material, the platform 19 may be unlatched and lowered toward the dot-and-dash 50 location indicated in Fig. 3, the mother sheet may be placed under platform 16, and platform 19 may be elevated and again latched in place by catch 22. If the mother sheet is of translucent material, and there 55 is not enough natural light, bulb 26 is lighted; and also bulb 25, if desired, the latter to send its rays through window 15 of tube 8. If the mother sheet is of opaque material bulb 25 is lighted. When, 60 during shifting of the mother sheet as

aforesaid relative to platform 19, an acceptable design is seen through the eye or upper end of tube 8, a permanent indicium is made on the other sheet, as by the device and method of my said co-pending application, 70 to mark off the particular area of the mother sheet which, constituting the repeat element of the accepted design, generated the latter by way of the well-known action of the kaleidoscope tube. This mother sheet 75 is then removed from the apparatus, turned over to the artist, and from such mother sheet the artist prepares the optical interponent 27 as above described. Thereupon this interponent 27 is placed under the guiding control of platform 19 and also of rails 23 and 24 and 23' and 24', and the same apparatus is used to carry out the above-described method of design-development as to color scheme. 80 85

It will thus be seen that the present invention also provides a method of design-creation which may be said to involve shifting a mother sheet interponent relative to a kaleidoscope tube to create a design including a plurality of identical repeat elements, making a plurality of copies of such an element, applying dissimilar colorings to the identical configurations of each such copy, and successively disposing the various copies relative to the same tube to reproduce a succession of said designs, each complete but each according to a different color scheme. 90 95

It will further be seen that the present invention provides, as a new article of manufacture, a color sheet interponent for a kaleidoscope design-developer, said sheet being provided, preferably on the same face thereof, with a plurality of similar, and preferably identical, polygonal areas, each area carrying the same design as to configuration but a different design as to color scheme. In the present case said areas are arranged in column lengthwise of an elongate sheet, 100 or strip, and with the areas arranged so that each characteristic bounding line thereof is parallel to the same bounding line of an adjacent area. The purpose of the feature last mentioned is of course to facilitate 105 the instantaneous substitution of one area for another relative to a fixed tube, merely as the result of shifting the strip interponent in a straight-line path parallel to the length of the interponent. As to the feature of the invention now being discussed, such feature may be more broadly described as involving an arrangement of the areas on a color-scheme interponent such that one bounding line of one area (see line *a*, Fig. 1), is extended at the same angle to a bounding line of another area (see line *b*), as the bounding line of the last-mentioned area (line *a'*), corresponding to the first-mentioned bounding line of the first-mentioned area (line *a*), 110 115 120 125 130

is extended relative to a bounding line of a third area (line b'), corresponding to the first-mentioned bounding line of the second-mentioned area (line b); as would describe 5 a color scheme interponent of disk type pivoted at its center and having the areas arranged symmetrically relative to such center, and where of course a fractional rotation of the disk moves the areas in the 10 path predetermined to substitute one area for another relative to the tube.

Variations may of course be resorted to within the scope of the following claims:

I claim:

1. The method of kaleidoscopic design-development, which involves providing a kaleidoscope tube having a reflecting chamber of polygonal cross-section, providing a single color-sheet interponent carrying a 20 plurality of polygonal designs each disposed within an area similar in shape to the cross-section of the reflecting chamber of the tube, each such design having similar design configurations but with certain of such configurations in each area differently colored, and shifting the interponent relative to the tube to substitute one of said designs for another for kaleidoscopic reflection within the tube. 25

2. The method of design-creation, which involves providing a kaleidoscope tube, providing and shifting a mother sheet interponent relative to the tube to generate a design including a plurality of identical repeat elements, making a plurality of copies 30 of such repeat elements, applying dissimilar colorings to the same configurations of each such copy, and successively disposing the various copies relative to a kaleidoscope tube to reproduce a succession of said designs, each complete but each according to 35 a different color scheme.

3. As a new article of manufacture, a color sheet interponent for a kaleidoscopic design-developer, said sheet having a plurality of similar polygonal areas each having the same design as to configuration but 45 a different design as to color scheme.

4. As a new article of manufacture, a color sheet interponent for a kaleidoscopic design-developer, said sheet having a plurality of identical polygonal areas each having the same design as to configuration but a different design as to color scheme, all 50 said areas being on the same face of the sheet.

5. As a new article of manufacture, a color sheet interponent for a kaleidoscopic design-developer, said sheet having a plurality of identical polygonal areas each having the same design as to configuration but a different design as to color scheme, said 55 areas being arranged in column.

6. As a new article of manufacture, a color sheet interponent for a kaleidoscopic

design-developer, said sheet having a plurality of identical polygonal areas each having the same design as to configuration but a different design as to color scheme, said areas being arranged so that each characteristic bounding line of an area is parallel to 65 the same bounding line of an adjacent area. 70

7. As a new article of manufacture, a color sheet interponent for a kaleidoscopic design-developer, said sheet having a plurality of identical polygonal areas each having 75 the same design as to configuration but a different design as to color scheme, said areas being arranged so that one bounding line of one area is extended at the same angle to a different bounding line of another area, as the bounding line of the last-mentioned area, corresponding to the first-mentioned bounding line of the first-mentioned area, is extended relative to a bounding line of a third area corresponding to 80 the first-mentioned bounding line of the second-mentioned area. 85

8. In kaleidoscopic apparatus, the combination of means for supporting a kaleidoscope tube in a selected position, means for holding an optical interponent for the tube to a plane substantially perpendicular to the line of extension of the tube while permitting movement of the interponent in such plane, and means for limiting the last-mentioned movement of the interponent to a predetermined path in such plane, said holding means being spaced from said limiting means and from the tube-supporting means to permit a second optical interponent to be employed of such smaller size as to be independent of the control of the limiting means. 90 95

9. In kaleidoscopic apparatus, supporting and guiding means for a shiftable optical interponent comprising a platform having an opening therein and adapted to support a kaleidoscope tube above such opening, a second platform below the first platform and having an opening therethrough under the opening in the first platform, said platforms being substantially parallel but spaced to permit an optical interponent to be shiftable carried between the platforms, a source of illumination above the upper 100 platform and to one side of its opening, and a source of illumination below the lower platform and to one side of its opening. 110 115

10. In kaleidoscopic apparatus, supporting and guiding means for a shiftable optical interponent comprising a platform having an opening therein and adapted to support a kaleidoscope tube above such opening, and a second platform below the first platform and having an opening therethrough, 120 and hinge and catch means for the lower platform whereby the latter may be held 125 slightly spaced from and substantially par-

allel with the first platform and may be swung downwardly away from the first platform.

11. In kaleidoscopic apparatus, supporting and guiding means for a shiftable optical interponent including a plurality of guides several of which are fixed and one of which is movable.

12. In kaleidoscopic apparatus, supporting and guiding means for a shiftable optical interponent including a plurality of guides one of which is a pivotally mounted guide plate and another of which is a fixed guide rail.

WALTER C. HADLEY.
